CLAIM

The ornamental design of a shelf divider for display of bagged food items, as shown and described.

DESCRIPTION

FIG. 1 is a perspective view of the design showing the left front and top sides thereof.

FIG. 2 is a front view of the design.

FIG. 3 is a rear view of the design.

FIG. 4 is a left side view of the design.

FIG. 5 is a right side view of the design.

FIG. 6 is a top view of the design; and,

FIG. 7 is a bottom view of the design.

The areas immediately adjacent to the dash dot dash lines in the drawing figures represent the bounds of the claimed design while the broken lines in the drawing figures represent environment and do not constitute part of the claimed design.

1 Claim, 3 Drawing Sheets

FIG. 1

FIG. 2

FIG. 3

FIG. 4

FIG. 5

FIG. 6

FIG. 7
